UNITED STATES PATENT OFFICE.

GEORGE GILL, OF TAUNTON, MASSACHUSETTS, ASSIGNOR TO REED & BARTON,
OF SAME PLACE.

DESIGN FOR A CAKE-TAZZA.

Specification forming part of Design No. 5,442, dated December 19, 1871.

To all persons to whom these presents may come:

Be it known that I, GEORGE GILL, of Taunton, of the county of Bristol and State of Massachusetts, have invented or produced a new ornamental Design for a Cake-Tazza; and do hereby declare the same to be fully described in the following specification and represented in the accompanying drawing, which denotes an elevation of the tazza.

The bowl of the article shown at A is in external form an inverted curved conic frustum, a, surmounted by a short conic frustum, b. Surrounding the lower part of the base are a series of stemmed drooping leaves, with fern leaves between their stems and in bas-relief on the part a. The base rests on a stand, C, having a series of ornamented legs, c, as shown, each terminating in a barbed human face, d, resting on a sphere

or ball, d'. A scroll-leaf, e, extends back from each of the said faces, as shown. The several legs have an ornamental connection annulus, f, arranged between them and connected to them by voluted and curved struts g h, arranged as represented, the conformations of the various members described being as shown in the drawing.

What I claim in the said tazza is—

The design of the stand C.

Also, the construction of such with the stemmed and fern leaves springing from such stem around the bottom of the bowl A.

Also, the design of the bottom of the bowl and the series of fern and stemmed leaves, as shown.

GEORGE GILL.
